US0D1040785S

(12) **United States Design Patent** (10) **Patent No.:** **US D1,040,785 S**
(45) **Date of Patent:** **** Sep. 3, 2024**

(54) **PAIR OF EARPHONES**

(71) Applicant: **Shenzhen Shengling Technology Co., Ltd**, Shenzhen (CN)

(72) Inventor: **Hua Lin**, Shenzhen (CN)

(**) Term: **15 Years**

(21) Appl. No.: **29/943,039**

(22) Filed: **May 20, 2024**

(30) **Foreign Application Priority Data**

Mar. 21, 2024 (CN) 202430146917.7

(51) **LOC (14) Cl.** **14-01**

(52) **U.S. Cl.**

USPC **D14/223**

(57) **CLAIM**

The ornamental design for a pair of earphones, as shown and described.

DESCRIPTION

FIG. 1 is a perspective view of a pair of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the pair of earphones shown in an environment of use.

The broken line showing of a case in FIG. 9 depicts environment that forms no part of the claimed design. All other broken lines shown in the drawings depict portions of the pair of earphones that form no part of the claimed design.

1 Claim, 9 Drawing Sheets
